GRADING APPARATUS

Harold R. Lewis, Hoopeston, Ill., assignor to Food Machinery Corporation, San Jose, Calif., a corporation of Delaware

Application May 22, 1931, Serial No. 539,272

5 Claims. (Cl. 209—289)

This invention relates to grading apparatus of the type adapted to grade granular material such as peas or the like according to size.

Apparatus of this character commonly used at the present time ordinarily comprises a series of perforated cylindrical drums or reels aligned in end to end relation along an axis slightly inclined from the horizontal so that as the reels are rotated in unison, peas or other granular material may pass from the initial or highest reel downwardly from reel to reel. The perforations of the several reels are progressively larger from the initial to the terminal reel so that as the peas pass through the rotating reels they are continuously rolled over the inner perforated surfaces of the reels and those peas of the sizes corresponding to sizes of the perforations are discharged therethrough into suitable receiving hoppers. In this manner as the peas pass through successive drums, the various sizes pass through the perforations of corresponding sizes in the several reels and are deposited with their proper groups.

It has been found that greatly improved results are secured from this type of machine if the initial reel is provided with perforations of such size that several sizes of peas may pass therethrough, and a secondary set of grading reels provided to regrade the peas passing through the perforations of this initial reel. These secondary or regrading reels have heretofore been placed beneath the primary or grading reels and receive the peas by gravity, and this construction necessarily requires considerable head room and results in decreased accessibility of the reels.

It is the primary object of this invention to provide a grading apparatus of the character referred to wherein the reels for regrading are not superposed thus decreasing the amount of head room required for the installation, and increasing the accessibility of the reels.

A further object is to construct a grading apparatus wherein all the reels, both primary and regrading are on substantially the same level and means are provided for receiving the discharge through the perforations of one or more of the primary grading reels and elevating this discharged material so that it can be fed to the regrading reels.

Other objects and advantages will become apparent as the description proceeds in connection with the accompanying drawing, it being understood that the apparatus disclosed is illustrative only and that many changes and modifications may be resorted to without departing from the

spirit of the invention, and I deem myself entitled to all such changes and modifications as fall within the scope of the claims hereto appended.

In the drawing:

Figure 1 is a side elevation of a grading apparatus embodying the features of my invention.

Figure 2 is a vertical sectional view taken along the line 2—2 of Figure 1 looking in the direction of the arrows.

Figure 3 is a vertical sectional view taken along the line 3—3 of Figure 1 looking in the direction of the arrows.

Like reference characters denote like parts throughout the several views.

The grading apparatus illustrated is of the rotary drum type and comprises a plurality of primary grading reels 1, 2, 3, and 4 arranged in axial alignment with their ends in abutting relation, and a series of secondary or regrading reels 5, 6 and 7 also arranged in axial alignment and on substantially the same level as the primary reels. In the apparatus shown there are provided two lines of reels identical in construction and arranged in side by side relation, but it will be understood that more than two lines may be utilized if desired, or only one line according to requirements, the invention being equally applicable to all such constructions.

The reels are provided with upstanding annular flanges 8 at their opposite ends which flanges are received in cooperating grooves provided in the rollers 9, which rotatably support the reels, the grooves in the intermediate rollers being of a width sufficient to receive the abutting flanges of two adjacent reels whereby the reels are held in position and prevented from separating. The rollers 9 are secured to shafts 10 extending longitudinally of the apparatus and supported by cross members 11 of the framing 12. The two inner shafts 10 are geared together by gears 13, and one of these shafts is driven by a belt 14 passing around the pulley 15. The belt 14 is driven by the pulley 16 keyed to a shaft 17 which is driven by a pulley 18 from any suitable source of power. By the construction just described the reels are supported upon and rotated by the supporting rollers 9.

Preferably the reels are rotated in the direction of the arrows and are slightly inclined from the horizontal to assist the peas to pass therethrough. A split feed hopper 19 is adapted to receive the peas to be graded and discharges them into the initial grading reels 1. In the construction illustrated the initial reels 1 are provided with perforations of #3 size so that all peas of this size or

smaller will pass through the perforations of this reel as it is rotated. The reels 2 are also provided with perforations of the #3 size in order to insure the separation in this reel of any peas which were of suitable size to pass through the perforations of the initial reels, but which are unavoidably carried over into reels 2 in the endwise discharge from reels 1 due to the large bulk of peas in the initial screens. Reels 3 and 4 are provided with perforations of #4 and #5 sizes respectively so that the peas of #4 size pass through the perforations of reel 3 into a hopper 20 from where they are discharged through a spout 21 into any suitable receiver not shown. The #5 peas pass through the perforations of the screen 4 into a similar hopper 22 and all peas of #6 size or larger are "tailed" over the end of reel 4 into the hopper 23.

It will be noted that the hoppers 24 beneath the reels 1 are interconnected as are also the hoppers 25 beneath the reels 2 (see Figure 3) and these hoppers are adapted to discharge onto an endless conveyor 26 positioned beneath and between the reels. The conveyor 26 is composed of a series of articulated buckets 27 running in guides 28 and the conveyor passes around suitable sprockets 29 and 30. The sprocket 30 is driven from shaft 31 through the medium of gears 32 and 33 and pulley 34 thus operating the conveyor in the direction of the arrows. As illustrated, the conveyor is elevated at its discharge end so that the peas discharged therefrom are received by the split feed hopper 35 which directs the peas into the regrading reels.

The regrading reels 5 and 6 are provided with #1 size perforations while regrading reels 7 have #2 perforations. These reels operate to separate the peas in exactly the same manner as the primary reels, the peas of #1 size being discharged into the hoppers 36 and 37; those of #2 size into the hopper 38; and the #3's being tailed over the end of reel 1 into the hopper 39.

In operation the peas to be graded are fed by any suitable means into the split hopper 19, half of the peas being directed into each line of reels. As the reels are rotated, the mass of peas moves toward the discharge end of the reels due to their inclination, being all the while tumbled and rolled about over the inner surfaces of the reels. In this manner the various sizes of peas pass through the correspondingly sized perforations in the several reels and are deposited with their proper groups. All the numbers 1, 2 and 3 sizes pass through the perforations in the reels 1 and 2 and are received by the conveyor 26 which elevates them and discharges them into the split feed hopper 35 from where they enter the regrading reels. These peas are then separated into their respective groups by the regrading reels as described above.

It is believed that the advantages of this construction will now be apparent. The primary grading reels and the regrading reels being on substantially the same level, the vertical clearance required for the apparatus is reduced to a minimum, and all of the reels are easily accessible. The feeding means for the peas to be regraded is positive and gentle in operation and there is no possibility of clogging.

While I have described the apparatus in connection with the grading of peas, it will be understood that it may be used with other granular material as well, and the term peas as used throughout the description is to be construed as including such other materials.

Having now described my invention and in

what manner the same may be used, what I claim as new and desire to protect by Letters Patent is as follows:—

1. In an apparatus for grading granular material, a plurality of primary cylindrical grading screens arranged in axially aligned endwise abutting relation whereby each succeeding screen receives the endwise discharge from the screen forwardly thereof, a secondary cylindrical grading screen having its axis disposed in substantially the same horizontal plane with the axes of the primary screens, said secondary grading screen being spaced from the primary grading screens, a single endless elevating conveyor disposed to one side of said primary grading screens and having a receiving portion lower than a forward primary grading screen whereby to receive the discharge therefrom by gravity, said elevating conveyor having an inclined portion extending upwardly beside the primary grading screens to convey the material received by its receiving portion to an elevated point of discharge, chute means beneath a forward primary grading screen for receiving material discharged therethrough and directing it to the receiving portion of said conveyor, and chute means disposed to receive the discharge from said conveyor and direct it into the secondary grading screen. 80

2. In an apparatus for grading granular material, a plurality of primary cylindrical grading screens arranged in axially aligned endwise abutting relation whereby each succeeding screen receives the endwise discharge from the screen forwardly thereof, a secondary cylindrical grading screen disposed in coaxial alignment with the primary screens and spaced therefrom, an endless elevating conveyor disposed to one side of said primary grading screens and having a receiving portion lower than a forward primary grading screen whereby to receive the discharge therethrough by gravity, and having an inclined portion extending upwardly beside the primary grading screens to elevate the material received by its receiving portion and discharge the same to the secondary screen for regrading, a common drive shaft for said primary and secondary screens extending alongside thereof, and means on said drive shaft for driving all of said screens. 100

3. In an apparatus for grading granular material, two lines of grading screens extending alongside each other, each line comprising a plurality of primary grading screens arranged in aligned endwise abutting relation whereby each succeeding screen receives the endwise discharge from the screen forwardly thereof, and a secondary grading screen spaced from said primary grading screens and having its axis disposed in substantially the same horizontal plane with the axes of the primary screens, an endless elevating conveyor extending upwardly between said lines of grading screens and having its receiving portion lower than the forward primary grading screens whereby to receive the discharge therethrough by gravity, said elevating conveyor being arranged to convey the material so received to an elevated point of discharge, chute means beneath certain of the forward primary screens of each line for receiving material discharged therethrough and directing it to the receiving portion of said conveyor, and chute means disposed to receive the discharge from said conveyor and direct a portion of it into each of the secondary grading screens.

4. In an apparatus for grading granular material, two lines of cylindrical grading screens

extending alongside each other, each line comprising a plurality of primary grading screens arranged in axially aligned endwise abutting relation whereby each succeeding screen receives the endwise discharge from the screen forwardly thereof, and a secondary grading screen disposed in coaxial alignment with the primary screens and spaced therefrom, an endless elevating conveyor extending upwardly between said lines of grading screens and having its receiving portion lower than the forward primary grading screens whereby to receive the discharge therethrough by gravity, said elevating conveyor being arranged to convey the material so received to an elevated point of discharge, chute means beneath certain of the forward primary screens of each line for receiving material discharged therethrough and directing it to the receiving portion of said conveyor, and chute means disposed to receive the discharge from said conveyor and direct a portion of it into each of the secondary grading screens.

5. In an apparatus for grading granular material, two lines of cylindrical grading screens extending alongside each other, each line comprising a plurality of primary grading screens arranged in axially aligned endwise abutting relation whereby each succeeding screen receives the endwise discharge from the screen forwardly thereof, and a secondary grading screen disposed in coaxial alignment with the primary screens and spaced therefrom, an endless elevating conveyor extending upwardly between said lines of grading screens and having its receiving portion lower than the forward primary grading screens whereby to receive the discharge therethrough by gravity, said elevating conveyor being arranged to convey the material so received to an elevated point of discharge, chute means beneath certain of the forward primary screens of each line for receiving material discharged therethrough and directing it to the receiving portion of said conveyor, and chute means disposed to receive the discharge from said conveyor and direct a portion of it into each of the secondary grading screens, a common drive shaft extending alongside the primary and secondary screens of each line, and means on each drive shaft for driving all of the screens of its corresponding line.
